TUMBLER

Frank Skupien, 5443 Wolcott St., Chicago, Ill.

Filed May 18, 1960, Ser. No. 60,640

Term of patent 14 years

(Cl. D36—8)

The ball shown illustratively by broken lines in Figs. 2 and 3 is freely moveable in the raceway provided. I claim:

The ornamental design for a tumbler, substantially as shown and described.
